HALSEY M. BARRETT, RECEIVERS FOR THE NATIONAL ELECTRIC SIGNALING COMPANY, OF PITTSBURGH, PENNSYLVANIA, A CORPORATION OF NEW JERSEY.

SPARK-GAP.

1,192,909.

Specification of Letters Patent. Patented Aug. 1, 1916.

Application filed August 31, 1914. Serial No. 859,432.

To all whom it may concern:

Be it known that I, FRED H. KROGER, a resident of Brooklyn, in the county of Kings and State of New York, have invented a new and useful Improvement in Spark-Gaps, of which the following is a specification.

This invention relates more particularly to spark gaps for generating oscillations in wireless telegraph apparatus and particularly the so-called "quenched gap" for this purpose. Its primary objects are to avoid the necessity of inclosing the sparking surfaces in an air-tight chamber and to cause a discharge to take place uniformly by traveling over continually cooled surfaces.

I have illustrated the invention in the accompanying drawing in which the figure is a side elevation partially in section on the left of the gap proper.

The usual form of the quenched spark gap, has been inclosed and the sparking electrodes stationary, but I have found that under proper conditions the gap need not be closed and has certain additional advantages hereinafter to be noted, when not inclosed.

In the accompanying drawing I mount upon the supports 1 and 2, the shaft 3 which is divided between the supports and on the sleeves 4 carries an insulating tube 5, upon which, clamped between screw thimbles 6 are the sparking plates 7, separated by insulating rings 8. These rings or washers 8 are carefully selected to give the proper separation between adjacent plates and it will be understood that the plates thus insulated from each other are carefully trued on a lathe and mounted to be perfectly parallel. The electric contact to the end plates 40 of the series may be made through the binding posts 9 and 10 on shaft 3.

The shaft 3 and the sparking plates 7 are caused to slowly rotate by means of worm gearing 15, 16, 14, 13, the latter being on the shaft 12^a of a small motor 12, which is also used to operate a fan 11 having a flared horn or nozzle 11^a to distribute the air and blow it between and around the disks 7.

The horn 11^a of the fan 11 is made of insulating material and serves as a dielectric or electrostatic attractor which has the effect of concentrating the lines of force in the electrostatic field and causing the spark to

occur near said dielectric and therefore to travel over the surface of the plates 7, as they slowly rotate past the insulating material.

The construction described has several advantages, among which are the great ease of inspecting and cleaning; the traveling of the charge around the circumference of the disks, thereby securing uniformity; and the efficient cooling of the sparking plates. I have also found the peculiar phenomenon that the noise from this gap is an indication of the proper adjustment of circuits, in that there is very little noise when the tuning of the circuits is correct, the sparking not then occurring at the edges, whereas when the circuits are slightly out of adjustment, the gap becomes noisy and the sparking does occur at the edges. This gives the operator a constant reminder of the state of his tuning, which is a very valuable quality.

Other advantages of the device will readily occur to those skilled in the art.

What I claim is:

1. A spark gap, comprising a series of insulated disk electrodes in parallel planes and arranged to rotate on a common axis, and a stationary dielectric near the peripheries of said disks and having longitudinally extending portions opposite the gaps therebetween to cause the sparks to substantially remain stationary as the disks revolve.

2. A spark gap, comprising a series of parallel disks insulated from each other and mounted on a shaft, means for rotating said shaft, a blower, and a nozzle connected thereto to distribute air between and around said disks, said nozzle being made of insulating material and mounted near the edge of the disks and serving as a dielectric to cause the spark to travel over the surfaces of the disks as the disks revolve.

3. In wireless telegraphy apparatus, a quenched spark gap, comprising a rotating insulated shaft, a series of flat-faced disks insulated from each other on said shaft, a device to continually cool said disks, and a continuous dielectric opposite the edges of said disks to govern the position of the sparks on the disks as they revolve.

In testimony whereof, I have hereunto set my hand.

FRED H. KROGER.
